LIQUID CONTROL DEVICE FOR DUPLICATING MACHINES

Eric W. Peterson, Oak Park, Ill., assignor to Ditto, Incorporated, Chicago, Ill., a corporation of West Virginia

Application October 14, 1940, Serial No. 361,068

16 Claims. (Cl. 91—49)

This invention relates to a liquid control device for duplicating machines.

Wet process duplicating machines are provided with a drum to which a master sheet may be secured, the characters on the master sheet being written in reverse in a soluble ink. A pressure roll is also provided which bears against the drum and is adapted to press a copy sheet against the master sheet so that a small amount of the ink, which forms characters on the master sheet, may be transferred to the copy sheet. Means are provided for applying a small amount of solvent to the surface of the copy sheet as it is being fed to the bight of the drum and pressure roll. The legibility and clearness of the characters formed on the copy sheet, as well as the number of copy sheets which may be used with each master sheet, are determined in large measure by the amount of solvent applied to the surface of the copy sheet.

Certain types of moistening means require priming after a period of non-use. The priming means in the duplicating apparatus herein described is associated with the means which regulate the amount of solvent applied to the copy sheet. Although duplicating apparatus of this type may be provided with a motor which not only drives the drum but also causes operation of the moistening means, it is desirable to perform the priming operation manually inasmuch as the priming may be more closely controlled. Over-priming will ruin the master sheet.

An object of my invention is to provide improved means for controlling the moistening mechanism of a wet process duplicating apparatus.

A further object is to provide improved means for controlling the amount of solvent which is supplied to the moistening means for subsequent application to a copy sheet.

A still further object is to provide means whereby the priming operation must be performed manually and whereby the priming mechanism will automatically become inoperative at the conclusion of the priming operation.

Still another object is to provide a combined control means for both regulating the amount of solvent supply and for priming the moistening means.

Other objects, features and advantages of my invention will become apparent as the description proceeds.

Referring now to the drawings in which like reference numerals represent like parts:

Fig. 1 is an elevation of a preferred embodiment of my invention, a portion of the side frame member being broken away to more clearly illustrate the parts;

Fig. 2 is an enlarged sectional view taken along line 2—2 of Fig. 1;

Figs. 3, 4 and 5, are sections taken along lines 3—3, 4—4, and 5—5, respectively, of Fig. 2; and

Figs. 6, 7 and 8 are perspective views of certain of the parts shown in Fig. 2;

10 Referring now to Fig. 1, reference numerals 10 and 11 represent the two side frame members of a duplicating machine, the side frame member 11 being broken away. A front frame member 12 and a rear frame member 13 are also provided. A drum 14 is suitably journaled in the side frame members and a pressure roll 15 is suitably mounted for cooperation therewith. A moistening and upper feed roll 16 is also rotatably journaled in the side frames, and a lower feed roll 17 is resiliently mounted for cooperation therewith.

15 A moistener indicated generally by reference numeral 18 is mounted adjacent the upper feed roll 16 and functions so as to apply a thin film of solvent to the surface of the roll. The moistener may be any one of a number of types, the one being shown herein being of the type in which solvent is supplied directly onto the surface of the upper feed roll by means of a pump 19, and

20 in which a wiper may be employed to distribute the solvent uniformly over the surface of the upper feed roll.

25 A tank 20 is provided at the rear portion of the machine, a portion of the tank being broken away to indicate the pump 19 which is mounted therein. The pump includes a plunger 21 which extends upwardly through the top of the tank, the plunger being adapted to be raised, by means hereinafter described, on its inoperative stroke 30 and being provided with a spring 22 to urge the plunger downwardly for its operative stroke. A conduit 23 leads from the pump 19 to the moistener 18, the tank being provided with a filling pipe 24 and a liquid level gauge 25.

35 A feed tray 26 is positioned above the tank at the rear end of the machine and a receiving tray 27 is mounted at the front end of the machine.

40 A motor 28 is suitably mounted at the rear end and is provided with a pulley 29 over which a belt 30 passes to drive the pulley 31. A pulley 32, associated with the pulley 31, drives a pulley 34 by means of a belt 33. A pinion 35 is affixed to the pulley 34 and meshes with a gear 36 which is affixed to the drum 14. A gear 37 may be associated with the drum, either directly or

by means of an intermittent driving means, this gear meshing with an intermediate pinion 38 which drives a pinion 39. The latter pinion is secured to the upper feed roll 16 so that the feed roll may be driven from the drum. The above mentioned intermittent driving means may be employed when it is desired to rotate the drum continuously so that the feed rolls may be interrupted in order that a copy sheet may be positioned against the feed rolls. A trip bar 40 is provided to control the operation of the motor. The intermittent driving means and the motor controlling means are not a part of this invention and are not herein disclosed in detail.

Means are provided to bias the pressure roll 15 against the drum 14, and a pressure control knob 41 is provided for the regulation of such pressure. Means for biasing the lower feed roll 17 against the upper feed roll 16 are also provided, the last named means also being under the pressure control knob 41. These means are described in detail in the pending application of Robert F. Morrison, Serial No. 354,981 which was filed August 31, 1940.

A handle 42 may be provided for the actuation of gripping means for the master sheet through the intermediation of the expanding cams 43. A master sheet feed tray 44 may also be provided for cooperation with said gripping means. The details of this are not a part of this invention but are disclosed in Patent No. 2,195,491 which issued April 2, 1940 to Alfred Marchev.

This invention is primarily concerned with the solvent supplying mechanism and the control means therefor. As indicated above, the general type of moistening means with which the solvent supply mechanism is associated, is the one which is supplied with a measured amount of liquid during each cycle of the machine's operation. Thus the requisite amount of solvent is available for the proper moistening of each copy sheet irrespective of the rate at which the copy sheets are fed into the machine.

In the preferred embodiment herein disclosed this result is accomplished by means of the pump 19 which is automatically operated once during each revolution of the drum. Adjusting nuts 45 are provided at the upper end of the pump plunger 21 and a washer 46 is located on the plunger immediately below the adjusting nuts to serve as a bearing surface for the end of the pump lever 47. The pump lever is pivoted upon a stud 48 extending inwardly from the side frame member 11 and the lower end of the pump lever 47 terminates in a roller 49. A forwardly extending actuating arm 50 is also pivoted on the stud 48 and is suitably secured to the pump lever 47. A cam rider in the form of a roller 51 is provided at the upper end of the actuating arm and cooperates with a cam 52 which is secured to the drum 14. It will be seen that with every revolution of the drum, the cam 52 will cause the cam roller 51 and the pump lever 47 to be slowly rotated in the clockwise direction, thereby lifting the pump plunger 21. At a predetermined point in the rotation of the drum, the drop portion 53 of the cam 52 will permit the spring 22 to force the plunger 21 downwardly and to supply a measured amount of solvent to the moistener 18; the quantity of solvent thus supplied is determined by regulating the length of the pump stroke.

As indicated in Fig. 2, the side frame 11 is apertured and is provided with a boss 54 which extends inwardly therefrom so that a shaft 55

may be journalled therein. A knob 56 is suitably secured to one end of the shaft 55 and a cam member 57 is suitably secured to the other end of the shaft, the cam member being on the inward side and the knob being on the outer exposed side of the frame member. The cam member 57 is provided with an arm 59 which limits the rotation of the member in clockwise direction in Fig. 4. At the opposite end of the operative cam face of the member, a recess 60 is provided, with a projecting portion beyond the recess serving to limit rotation of the member in counter-clockwise direction in said Fig. 4.

A dial 61 is secured to the outer surface of the side frame member 11 and is provided with indicia 62 thereon. A pointer 63 is secured to the knob 56, the pointer cooperating with the indicia to indicate the position of the cam 57. When the knob is manually rotated so that the pointer is opposite "0" it will be seen that the cam is rotated into one extreme position so that the projection 59 is positioned against the roller 49. The pump lever 47 is thus displaced in the clockwise direction as viewed in Fig. 1 so that the pump plunger 21 is withdrawn to its extreme upper limit, and the roller 51 is held out of engagement with the cam 52. Rotation of the drum and the cam 52 will not cause operation of the pump when the cam is in this position. When the pointer is opposite "1," the plunger 21 is withdrawn to a somewhat lesser extent, and the roller 51 is held in a position wherein it may be engaged so as to actuate the pump plunger to a limited extent. Similarly as the pointer is turned in the clockwise direction, the pump displacement will be greater, and more solvent will be supplied to the moistener 18 with each revolution of the drum.

A series of apertures 64 are formed in the dial 61, these apertures extending from the indicium "0" to the indicium "4." A pin 65 is provided on the point or member 63, which is adapted to fit into any one of the apertures 64, so that the knob and the cam may be locked into its adjusted position. Compression spring 66 is positioned between the boss 54 and the cam 57 to urge the knob inwardly and the pin 65 into one of the apertures 64.

After the machine has been standing idle for a period of several hours it is necessary to prime the moistener 18, and this is effected by withdrawing the knob and rotating it back and forth so that the pointer moves to and from the "P" position. The number of such priming strokes necessary is determined by the type of moistener used. In any event this must be a closely controlled operation inasmuch as too much priming will cause damage to the master sheet. The priming strokes cause the cam 57 to be rotated so that the pump lever 47 is caused to oscillate, the roller 49 riding in and out of the recess 60, thereby manually actuating the pump plunger 21. Subsequent to the priming operation, the knob may be rotated back into the desired position for normal operation, for instance to a position wherein the pointer is opposite "2" or "3."

To guard against the possibility that the cam 57 might be left in the priming position during subsequent operation of the machine, and thereby cause the master sheet to be damaged, provision is made to automatically cause return of the cam to a position wherein the length of the pump stroke is limited. This is accomplished by providing a slot 68 in the boss 54, and another slot 67 in the cam 57. The compression spring 66

is provided with a bent-over end 60 which extends into the slot 66, and a bent-up end 70 which fits into the slot 61. When the parts are assembled the spring 68 may be tensioned so that the spring 68 causes the cam 57 and its associated parts to be tensioned in counterclockwise direction as viewed in Fig. 1, or the clockwise direction as viewed in Fig. 4. The compression spring thus acts also as a torsion spring to cause rotation of the knob 56 away from its priming position to the "4" position, at which point the pin 65 drops into one of the apertures 64. In this position, the cam 57 restricts the amplitude of oscillation of the lever 47 to such an extent that the master sheet will not be damaged by too great a solvent supply.

It will be noted that the pump spring 22, through the medium of the pump lever 47 and the roller 49, acts on the cam 57 in opposition to the spring 68. If the recess 60 is of sufficient depth, the spring 68 may not be strong enough to cause the roller 49 to be lifted out of the recess. However, as soon as the motor is started, the cam 52 causes displacement of the lever 47 so that the roller 49 clears the detent, thereby permitting the cam 57 to be rotated away from its priming position.

Because of the fact that the action of the spring 68 opposes the action of the pump spring 22, the manual priming operation is facilitated.

It will be seen that in the construction herein shown the pump may be actuated manually for the priming operation, or automatically during normal operation of the machine. The knob 56 is used for both the manual priming operation and also to regulate the length of the pump stroke during automatic operation of the pump. The control means herein disclosed prevent the pump from operating with a full stroke during automatic operation.

While the preferred embodiment of the invention has been shown, it is to be understood that it is capable of many modifications. Changes, therefore, in the construction and arrangement of the parts may be made without departing from the spirit and scope of the invention as described in the appended claims, in which it is my intention to claim all novelty inherent in my invention as broadly as possible, in view of the prior art.

I claim:

1. A wet process duplicating machine comprising driving means, moistening means, priming means for said moistening means, and means to render said priming means inoperative during operation of said driving means.

2. A duplicating machine comprising a moistening device, a pump for supplying solvent thereto, automatic means for actuating said pump, manual control means for regulating the displacement of said pump and also adapted to actuate the same manually, means to lock said control means in certain positions, and means to bias the same into one of said positions during actuation of said pump by said automatic means.

3. A duplicating machine comprising a moistening means, a pump for supplying solvent to said moistening means, a plunger for said pump, a rotatable cam for causing reciprocation of said plunger, means for rotating said cam, manually controlled means associated with said plunger for reciprocating said plunger at full stroke to prime said moistening means, and means for causing said manually controlled means to become locked in a position wherein the stroke of said plunger

is limited during operation of said rotatable cam.

4. A duplicating machine comprising a moistening means, a pump for supplying solvent to said moistening means, a plunger for said pump, a rotatable cam for causing reciprocation of said plunger, means for rotating said cam, a manually reciprocable cam associated with said plunger and provided with a detent to indicate full stroke position of said plunger, means biasing said manually reciprocable cam into a position wherein the stroke of said plunger is limited when said plunger is reciprocated by said rotatable cam, and means for releasing said detent when said rotatable cam begins to rotate.

5. Solvent control means for a duplicating machine comprising a pump, automatic means for operating said pump, manual means for operating said pump, said manual means being adapted to remain set in certain predetermined positions to limit the displacement of said pump during operation of said automatic means, and means for causing said manual means to move into one of said predetermined positions when said automatic means begins its operation.

6. Solvent control means for a duplicating machine comprising a pump, automatic means for operating said pump, a manually actuated cam for operating said pump, said manually actuated cam being adapted to remain set in certain predetermined positions to limit the displacement of said pump, and spring means for causing said manually actuated cam to move into one of said predetermined positions when said automatic means is operative.

7. Solvent control means for a duplicating machine comprising a pump, automatic means for operating said pump, a cam adapted for manual oscillation for operating said pump and adapted to control the pump displacement during automatic operation, means to lock said cam in certain predetermined positions corresponding to certain lesser degrees of displacement of said pump, and means biasing said cam from a position corresponding to a greater degree of pump displacement into one of said predetermined positions whereby said cam may automatically assume its control function during automatic operation of said pump.

8. In a duplicating machine, a pump plunger for supplying solvent to a moisture, spring means to actuate said plunger on its operative stroke, a lever to actuate said plunger in opposition to said spring means, manual control means engaging said lever to limit the stroke of said plunger, and capable of manual oscillation for manually operating said plunger, means for biasing said control means into a locked position wherein said stroke is limited, and means engaging said lever to cause automatic operation of said plunger and to cause said lever to become disengaged from said manual control means so as to permit said biasing means to become operative.

9. In a duplicating machine, a moistener requiring priming, a pump for supplying solvent thereto, a pump lever, a spring acting on said pump lever for operating said pump, manual control means associated with said pump lever and adapted to be locked in a position wherein the stroke of said pump is limited and adapted to be manually displaced therefrom for operating said pump to prime said moistener, second spring means acting in opposition to said first mentioned spring on said lever through the intermediation of said manual control means to facilitate the priming operation, and additional means engag-

ing said lever for operating said pump subsequent to said priming operation, whereby displacement of said lever by said additional means permits said second spring means to cause return of said manual control means to locked position.

10. Moistening means for a duplicating machine comprising a moistener, a pump for supplying liquid to said moistener, a pump comprising a plunger, a spring for moving said plunger in one direction, a pivoted member adapted by operative engagement with the plunger to move the plunger in the opposite direction, automatic means for oscillating said pivoted member, manual means for oscillating said pivoted member, and means for biasing said manual means into a predetermined position wherein it is engaged by said pivoted member to restrict the amplitude of oscillation thereof when actuated by said automatic means.

11. In a duplicating machine, a moistener, a pump for supplying solvent to said moistener, a pump actuating lever, a first cam for cooperation with said lever to automatically actuate said pump, a second cam cooperating with said lever for manually operating said lever and for restricting the oscillation thereof when actuated by said first cam, a knob associated with said second cam, means to lock the knob in a position to restrict the oscillation of said lever when actuated by said first cam, and means to cause automatic return of said knob into said locked position after manual manipulation thereof to manually operate said pump actuating lever.

12. Solvent control means for duplicating apparatus comprising a stop plate having a series of apertures therein, a manually adjustable knob provided with a projection for cooperation with said apertures, means to bias said knob against said plate in an axial direction, and means to bias said knob rotatably whereby after manual displacement, said knob will be automatically rotated back and locked into a predetermined position with respect to said stop plate.

13. Solvent control means for duplicating ap-

paratus comprising a rotatable and axially displaceable shaft extending through a frame member of said apparatus, a knob on said shaft exteriorly of said frame member, a control cam on said shaft interiorly of said frame member, a coil spring confined between said frame member and said cam, the ends of said spring being associated with each of said last named elements so that said spring exerts a torque on said shaft, and means to permit said shaft to be axially displaced by said spring into a predetermined position wherein it is locked against further rotation by said spring.

14. Solvent control means for duplicating apparatus comprising a rotatable and axially displaceable shaft extending through a frame member of said apparatus, a knob on said shaft exteriorly of said frame member, a control cam on said shaft interiorly of said frame member, means to lock said knob in a predetermined angular position, and a combination compression and torsion spring associated with said frame member and said cam to bias said knob into locked position.

15. A moistener control means for a duplicating machine comprising a manually adjustable priming knob, a stop plate, means to bias said knob axially against said stop plate, means for locking said knob in a predetermined rotatable position with respect to said plate and means to rotatably bias said knob into said predetermined position after the manual displacement thereof into priming position.

16. Moistener control means of the class described comprising a manually adjustable control and priming knob, means for locking said knob in certain predetermined positions corresponding to the normal operating adjustments of the moistener, and means to rotatably bias said knob into one of said predetermined positions after the manual displacement thereof into priming position.

ERIC W. PETERSON.
